HAND BLOWER DUST GUN

John A. Chater, Medina, Joseph B. Cary, Buffalo,
and Jacob E. Hollinger, Middleport, N. Y., as-
signors to Niagara Sprayer and Chemical Co.
Inc., Middleport, N. Y., a corporation

Application June 24, 1932, Serial No. 619,082

8 Claims. (Cl. 43—148)

This invention relates to the distribution of powders and the like, and more particularly to the depositing of insecticides and fungicides upon vegetation.

5 For a number of years it has been recognized that additional advantages resulted from the use of insecticides and fungicides when applied to growing vegetation in the form of a dust cloud, as the material was more uniformly deposited 10 upon the under faces of the leaves and other surfaces which were normally difficult to reach. Many machines have been constructed for this purpose and while some of them are very efficient in operation, the need for a light weight, 15 compact, large capacity, and efficient device, which could be manually carried and operated has been recognized; but a device completely fulfilling these requirements has not heretofore been produced.

20 The present invention is intended to fulfill the above noted requirements, and it is an object of this invention to produce a large capacity portable duster for hand operation which is compact and of good appearance, and which upon operation will produce a violently discharged but controllable dust cloud.

25 It is another object of the invention to provide a dust gun wherein the hopper for insecticides or other powders, and the blower compartment are in substantially the same horizontal alignment; and in which the powder is fed from the bottom of the hopper and thereafter elevated and delivered into the blower compartment from which it is discharged in the form of 30 a dust cloud while in a suspended condition in the discharged air.

35 The invention further contemplates the provision of means biased toward a predetermined adjusted position for controlling the amount of 40 material being discharged, which means may be instantaneously moved from the adjusted position for completely stopping the feed of the material to thereby permit the device to be operated as a "puffer device."

45 The invention still further contemplates the provision of a dust gun having the parts thereof positioned and shaped to permit ease of carrying and ease of controlling the discharge and operation of the crank handle, and the invention has 50 for an object the construction of such a device in a simple and inexpensive manner.

55 Other objects and advantages will be apparent from the following detailed description when considered in connection with the accompanying drawings wherein,

Fig. 1 is a perspective view of one form of the invention illustrating a complete device being carried by an operator, a form of harness or supporting straps which may be utilized for supporting the device also being illustrated, 60

Fig. 2 is a side elevation of the device shown in Fig. 1 with a part broken away to illustrate the material feeding and the blowing mechanisms,

Fig. 3 is a transverse sectional view through the blower housing taken on line 3—3 of Fig. 2, 65

Fig. 4 is a transverse sectional view through the air duct housing illustrating the valve for controlling the delivery of the material,

Fig. 5 is a fragmentary transverse sectional view through the hopper, 70

Fig. 6 is a transverse sectional view through the gear housing illustrating the means for supplying power to and effecting rapid rotary motion of the fan, and

Fig. 7 is a perspective view of a portion of the 75 partition casting which is arranged between the material hopper and the blower compartment.

Now referring to the drawings in detail:

The body of the device is indicated at 10, which body has extending forwardly therefrom a discharge pipe 11. A nozzle 12 is arranged at the forward end of the discharge pipe and this nozzle 12, as well as the discharge pipe 11, may be of any of the usual constructions now in use. The pipe 11 may be lengthened or shortened according to the character of the vegetation to be 85 dusted and the nozzle may also be modified although these parts in the form illustrated are efficient for many uses.

A harness or strap structure of any suitable 90 construction may be used for supporting the device upon the operator, the harness structure shown in Fig. 1 being very effective for distributing the weight. The construction illustrated is formed of a loop 13 at each side of the device with 95 the ends thereof attached to the dust gun body 10, a cross connecting strap 14 being provided for securing the loops together to effect the holding of the same upon the shoulders of the operator. In place of the one cross connecting strap 14, two 100 cross connecting straps may be used in such a manner that they are at right angles to each other being sewed together at their intersection. These cross connecting straps are adjustably 105 fastened to loop 13 in their respective positions by means of suitable buckles.

Upon referring to Fig. 2 it will be seen that the body 10 includes a material or dust hopper 15 which may be of any desired shape but which 110

for the purpose of compactness and appearance is preferably of cylindrical cross section. The hopper is provided with an opening 16 in its wall, and this opening is provided for permitting the 5 filling of the hopper with the material to be dusted. To provide a means for closing the opening in the hopper a curved sheet 17 is formed in a shape to conform to the cylindrical hopper wall and this cover sheet is pivoted to the hopper adjacent 10 a straight edge of the opening by means of a hinge 18. A pull ring 19 is provided to permit ready opening of the cover.

The hopper is closed at one end by a plate 20 which may be in the form of an aluminum casting 15 or may be a sheet stamped from thin steel. A tight connection is made between the plate 20 and the cylindrical wall of the hopper so that dust will not waste therebetween. When a stamped steel sheet is employed as the end 20 of the hopper, the joint may be welded. The opposite end 20 of the hopper is formed of an enlarged plate 21 which is bolted to a flange 22 surrounding the cylindrical wall of the hopper. This end of the 25 hopper, like the opposite end is made tight to assure the avoidance of waste.

Attached to the plate 21 and offset with respect to the center thereof is a circular cup-shaped casing 23 extending into the hopper and of sufficient size to accommodate a train of gears. A bearing 24 is mounted in the flat wall of the casing 23 at a point slightly below the center of the hopper, which bearing has a shaft 25 passing therethrough and into the casing 23. The extension of 35 the shaft 25 within the casing has a large gear 26 keyed thereon, while the opposite end of the shaft extends through a bearing 27 mounted in plate 20 and is constructed for the reception of a crank handle 28 by which the shaft is adapted 40 to be rotated.

Within the hopper the shaft is provided with openings for the reception of the ends of the generally U-shaped agitator 29, the connecting bar of which is angularly disposed with respect 45 to the shaft so that rotation of the shaft will cause the portion thereof adjacent the handle to travel in advance of the portion adjacent the gear casing. Due to this construction of the agitator it will effect the agitation of the material 50 within the hopper to thereby keep it in a fluffy condition, and it will also tend to feed or promote movement of the material in the direction of the plate 21.

An arcuate shaped opening 30 is provided in the 55 plate 21 adjacent the bottom of the hopper, and the opening is formed with a bordering flange 31 extending a short distance inwardly from the plate. The edge of this flange 31 is adapted to be engaged with or to be closely approached by extensions on a series of arms 32 forming a wiper spider 33. In the construction shown the spider 60 comprises six arms, each radiating from a hub 34, and a disc 35 lies adjacent the hub in order that the hub, disc and arms may be welded at 65 the points of contact to form a unitary structure.

The spider has its hub 34 mounted on the shaft 25 with an opening in the hub in registry with that opening in the shaft 25 nearest the plate 21, 70 and to assure maintenance of the spider in proper longitudinal position on the shaft and to cause the spider to turn with the shaft 25, one arm of the agitator 29 extends through the registering openings in the hub and shaft. This 75 arm of the agitator is secured in position by lock

nuts on each side of the shaft in a manner similar to the securing of the other arm of the agitator. The extensions on the arms, which act as wipers, are each flattened as at 36 and thereby a wiping of a predetermined quantity of material 80 through the opening 30 is effected substantially continuously as the spider is rotated. It will be seen that so long as material is contained within the hopper the agitator will maintain it in a loose condition and promote movement thereof generally toward the opening 30, and that the successive wipers will then deliver a predetermined quantity of the material through the opening as they wipe across the flange 31. A packing material 37 is arranged between the plate 35 and the bearing 24 and this packing prevents dust from passing into the casing 23.

An air duct and spacing casing 38 preferably in the form of an aluminum casting is mounted with a part thereof in contact with the plate 21. This casting 38 is provided with a slanting flange 39 from which extends a marginal flange 40 having openings registering with the openings by means of which the plate 21 and flange 22 of the hopper are bolted together. The bolts which pass through the plate and the hopper flange also pass through the openings in the marginal edge of the casting and secure the parts in position. At its lower portion the casting 38 is extended 100 downwardly to a point where the plate 21 and marginal edge 40 are secured together beyond the lower edge of the flange 22. In this portion the lower edge of the flange 22 is fastened to plate 21 by means of separate screws. The casting 38 is provided with an inverted U-shaped flange 41, which extends at right angles to the plate 21 and has its free edge contacting with said plate. At the point of contact between the flange and the plate, the joint is made substantially air tight 115 so that the space between the flange 39 and the flange 40 within the casting 38 will provide an air duct.

A series of openings are arranged in the upper portion of the flange 39 so that air may be 120 drawn into the air duct referred to, whereupon it passes downwardly around the ends of the arms of the inverted U-flange 41 and then upwardly between these arms. In order to eliminate air resistance as far as possible the arms of the 125 flange 40 are looped as at 41'. Casting 38 is further provided with an opening 42 disposed axially with respect to the shaft 25, which opening is in communication with a fan casing 43. The casing 43, which may be in the form of an aluminum 130 casting is mounted upon the wall of the casting 38 and the joint therebetween is made substantially air tight.

The flange 41 of the casting 38 is cut away as at 44 to receive a plate 45, the plate being securely 135 mounted in a position to bridge the arms of the flange. This plate 45 may be a part of the casting or may be formed separately and attached thereto consistent with the preferred mode of manufacture. A plate or valve 46 is pivoted to the plate 45 at 47, and the valve plate is provided with an extension at 48, the extension having a lever 49 attached thereto so that its end projects outwardly through a slot 50 in the casting 38. By this construction the movement of 145 the projecting portion of the lever 49 within the slot will cause the plate 46 to cover or partially cover the opening 30 depending upon the amount of material intended to be delivered. An adjustable stop is provided in the form of plates 150

adapted to be drawn together upon the casting wall surrounding the slot, by screw means 52. It will be seen that the loosening of the screw means will permit an adjustment of the stop member to any position within the slot 50, whereupon the plates may be drawn together and the stop thereby fixed in this adjusted position. A coil spring 53 or other suitable means is secured to the lever 49 and to the casing so that the 10 spring normally biases the lever against the stop to thereby normally bias the plate 46 in the direction for opening the slot 30. It will be further noted that even when the stop member 51 is adjusted to a position where the slot 30 will be partially open, it is only necessary for the operator to force the lever 49 away from the stop to effect the instantaneous closing of the slot 30. Such instantaneous closing of the slot will in no way interfere with the predetermined 20 adjustment of the stop member and therefore the release of the lever 49 will effect the movement thereof against the stop and the slot 30 will then be opened to the same extent that it was prior to its being temporarily closed.

25 Arranged within the casing 23 are shafts 54 and 55 respectively. The shaft 54 carries a gear 56 which meshes with the gear 26, the gear 56 being formed for movement with a large gear 57. Another small gear 58 is carried on shaft 55 and the shaft is so mounted that gear 58 is in mesh with gear 57. Gear 58 is fixed for rotation with a large gear 59. A shaft 60 supports a fan 61 in position adapted for rotation within the casing 43 and the shaft extends through a bearing 62 mounted in the plate 21 in axially alignment with the shaft 25. A gear 63 is mounted on the extension of the shaft 60 where it is in mesh with gear 59. The opposite end of the shaft 60 is carried in a bearing 64 mounted on the interior of the outer wall of casing 43. Bearings 62 and 64 are preferably in the form of ball bearings, and they are each provided with dust caps 65, which dust caps are constructed to permit the packing of grease therein and in the bearings so as to lubricate the bearings and exclude the dust therefrom. Fan 61 is securely mounted on the shaft 60 so that it will be properly aligned within the casing 43 when rotating at high speed. From the above, it will be seen that the operation of the handle 28 will not only effect the movement of the agitator and wipers but, due to the step up gearing within the casing 23, it will effect the very rapid rotation of the fan. As the fan is of a centrifugal type, a tangentially arranged outlet 66 is provided through which the fan may effect a discharge.

60 The casting 38 at the extreme lower portion thereof and directly below the slot 30 is formed with an upstanding deflector 67 so that the air which is drawn into the fan casing will be directed thereby and be caused to entrain such powder as is being delivered through the slot 30 as well as any powder which might have fallen upon the deflector.

65 The flange formed at the circumference of wall 20, and flanges 22, 40 and plate 21, are provided with a series of corresponding openings 68 to permit the attachment of the strap connections thereto for supporting the device upon the operator. The openings 68 are spaced along the flanges so that the strap connections may be adjusted therealong to cause the pipe 11 and the nozzle 12 to assume a position which leads itself to easy directing by the operator, depending upon the height and character of the vegetation treated.

A relatively wide plate 69 extends between the flanges and acts as a rest to engage against the body of the operator, the plate presenting a smooth substantially straight surface and thereby largely eliminating discomfort in supporting the device.

80 A handle 70 is angularly disposed in brackets from an upper point on the flange 22 of the hopper to a point of attachment on the fan casing 43, at which point the attached bracket is riveted to the casing. In using the particular construction employed to illustrate the invention, the hopper 15 being eight inches in length and of a proportionate diameter, as shown, is therefore of a comparatively large capacity. The material to be distributed is deposited in the hopper through the opening 16 and the cover 17 closed. Stop 51 may be adjusted to cause the opening 30 to be uncovered by the movement of the valve plate 46 to an extent sufficient to permit the 95 desired discharge of material.

95 When the device is supported upon the operator, the handle 70 is gripped for steadyng the same and for directing the discharge of the material. The crank handle 28 is operated and this movement causes the agitator 29 to fluff the material and tend to move the same in the direction of the plate 21. Wipers 36 move on the flange 31 and effect a continuous discharge of the material through the opening, and as the walls of the opening flare outwardly from the hopper, the material wiped into the opening falls readily therethrough. As the shaft 25 is about three-sixtieths of an inch below the center of the hopper, the agitator and wipers are closest to the hopper when they reach the bottom thereof.

100 At the initiation of the operation involving the feeding of the material through the opening 30 and into the casing 38, the fan is caused to rotate. As the fan illustrated is preferably five and one-half inches in diameter, and as the train of gears in the casing 23 is such that the fan is rotated sixty-four revolutions to each complete revolution of the crank handle, air at a high velocity is drawn into and discharged from the said 105 fan casing. The air is drawn in through the openings in the upper portion of the casing 38, then downwardly within the casting between the flange 39 and the inverted U-shaped flange 41, around the loops 41'; and then after being deflected and entraining the material which has been or is being delivered through the opening 30, the air with the material passes upwardly between the arms of the flange 41 and through the opening 42 and into the fan casing 43.

110 The material is violently agitated with the air in the fan casing and is lightly entrained in the air as it is discharged through the outlet 66. The dust laden air is thereafter passed into the pipe 11 and discharged through the nozzle 12 upon the 115 vegetation, as directed by the operator.

120 The quantity of material entrained in the air may be increased or decreased by adjusting the stop arranged in the slot 50. The adjustment of the stop will permit the lever 49 to be drawn thereagainst in the adjusted position by the 125 spring 53 so as to cause the valve plate to cover the slot 30 to a greater or lesser degree in accordance with the adjustment.

130 When the operator desires to discontinue the 145 feed of the material through the opening 30 while passing from one plant to another, or for any other reason, it is possible by using the thumb of the hand grasping the handle 70, to force the extension 48 away from the stop to a position 150

where the valve plate completely covers the opening 30. Release of the extension 48 when desired will then result in the spring causing the extension to abut the stop and the valve to assume the predetermined adjusted position. By such an operation the device is used as a "puffer" dust gun.

What we claim is:

1. A dusting device comprising a hopper compartment, a fan compartment arranged at the side thereof, the fan compartment being provided with an inlet opening in a plane above the lower portion of the hopper compartment, means for effecting delivery of material from the hopper compartment adjacent the lower portion thereof, and means for directing a current of air past the point of delivery of the material from the hopper to effect the entrainment of the material in the air for the elevation of the delivered powder into the fan compartment and the discharge of the material therefrom.

2. A dusting device comprising a hopper compartment, a fan compartment arranged at the side thereof, a spacing compartment forming an air duct arranged between the hopper compartment and the fan compartment, said spacing compartment being closed at its lower portion and being provided with an opening in its upper portion, an arcuate shaped partition provided in the spacing compartment having its ends curved away from the opening, said spacing compartment being provided with an opening communicating with the fan compartment arranged within the arcuate flange, means for delivering material from the hopper compartment into the spacing compartment, and a fan for drawing a current of air around the arcuate flange in the spacing compartment to entrain the material being delivered from the hopper compartment and to draw the air with the entrained material into the fan compartment to be discharged therefrom in the form of a dust cloud.

3. A dusting device comprising a hopper compartment, a fan compartment disposed in substantially the same plane therewith, an agitator within the hopper compartment, a train of gears in the hopper compartment, a casing enclosing the train of gears and having a bearing in its wall for the inner end of the agitator shaft, blower means including a shaft within the fan compartment, said shaft having one of the gears of the train of gears keyed thereto, means for delivering material from the hopper adjacent the lower part thereof, a conduit arranged between the place of delivery of the material from the hopper and the fan compartment through which the delivered material is elevated into the fan compartment for discharge therefrom while entrained in an air blast, and means mounted in the housing connected to the train of gears and the agitator for actuating the train of gears and for rotating the agitator.

4. A dusting device comprising a hopper compartment, a fan compartment and an intermediate compartment, means for delivering material from the hopper compartment into the intermediate compartment, means for drawing an air current through the intermediate compartment and into the fan compartment through a communicating passage, and a common means for effecting the operation of the air current drawing means and the material delivering means, said intermediate compartment being formed with an inverted generally U-shaped partition extending from the fan compartment to the hopper compartment with the

communication passage between the fan compartment and the intermediate compartment being between the arms of the inverted generally U-shaped flange.

5. A dusting device comprising a hopper compartment, a fan compartment and an intermediate compartment, annular flanges bordering the ends of the hopper compartment, said flanges being provided with a series of openings, means for supporting the device upon an operator, the supporting means engaging in selected openings in the flanges, said fan compartment being of smaller diameter than the hopper compartment, an angularly disposed handle connected at one end to the fan compartment and at the other end to the hopper compartment, means adapted for effecting a discharge of material from the device, means for directing the discharge of the material, and means for operating the discharge effecting means.

6. A dusting device comprising a hopper compartment, a fan compartment, an intermediate compartment, the compartments being rigidly secured together, a shaft within the hopper compartment, a crank handle adapted for rotating the shaft, a gear casing within the hopper compartment, bearings in the wall of the gear casing and in the wall of the hopper for the shaft, a wiping spider having a hub mounted on the shaft, an agitator having its ends extending through the shaft and secured thereto, one end of the agitator extending through the hub of the spider for keying the spider to the shaft, an opening providing communication between the hopper compartment and the intermediate compartment, the legs of the spider being angularly disposed and flattened to provide wiping surfaces which consecutively closely approach the rim of the arcuate opening during operation of the device, a train of gears in the gear casing, a fan in the fan compartment mounted on a shaft which extends through a bearing and into the gear casing, a gear on the fan shaft in mesh with one of the gears of the gear train for causing rapid rotation of the fan upon operation of the crank handle, said intermediate compartment being provided with a series of openings at the upper part thereof and with an inverted U-shaped flange extending from the hopper compartment to the fan compartment, the intermediate compartment being further provided with an opening near the center thereof for permitting communication with the fan compartment, a valve plate pivoted within the intermediate compartment and adapted to be moved for closing the opening to the hopper compartment, a lever on the valve plate extending through a slot in the intermediate compartment to the exterior of the device, a stop arranged for adjustment within the slot, means normally biasing the lever against the stop but permitting movement of the lever independently thereof, whereby operation of the crank handle will effect delivery of material into the intermediate compartment and the passage of an air current through the intermediate compartment around the lower ends of the inverted U-shaped flange so that the material will be entrained in the air and carried upwardly between the arms of the inverted U-shaped member and into the fan casing from which it will be discharged in the form of a dust cloud.

7. A dusting device comprising a hopper compartment and a fan compartment, an intermediate compartment into which material is delivered through an opening from the hopper compartment and through which air is drawn to entrain

- the material for conveying it through a communicating opening into the fan compartment, said intermediate compartment being provided with an inverted generally U-shaped flange bordering the 5 communicating opening between the fan compartment and the intermediate compartment, the opening for delivering material into the intermediate compartment being arranged adjacent the lower ends of the arms of the inverted U-shaped flange, and a deflector adjacent the delivery opening for effecting the directing of the incoming air so that it will be passed over the delivery opening for entraining the material delivered therethrough.
- 10 8. A dusting device comprising a hopper compartment, a fan compartment substantially co-
- extensive therewith, an agitator in the hopper compartment, a fan within the fan compartment, means for causing the operation of the agitator, means to operate fan, means for effecting the delivery of the material from the lower portion of the hopper, and means for directing a current of air past the point of delivery of the material from the hopper to effect the entrainment of the material in the air for carrying substantially all the material upwardly and into the fan casing 80 from which it is discharged in the form of a dust cloud.
